UNITED STATES PATENT OFFICE.

CHARLES McLEOD, OF TORONTO, CANADA, ASSIGNOR TO THE MASSEY-HARRIS COMPANY, OF SAME PLACE.

SEEDING-MACHINE.

SPECIFICATION forming part of Letters Patent No. 662,653, dated November 27, 1900.

Application filed September 19, 1899. Serial No. 731,020. (No model.)

To all whom it may concern:

Be it known that I, CHARLES McLEOD, manufacturer, of the city of Toronto, in the county of York, in the Province of Ontario, Canada, 5 have invented certain new and useful Improvements in Seeding-Machines, of which the following is a specification.

My invention relates to improvements in seeding-machines; and the object of the invention is to devise a simple and effective device to stop the crushing of the grain when it is being sown through the feed-run of this class of machine; and it consists, essentially, of a gate provided in the feed-run intermediate of its length and yieldingly held in position, the remaining portion of the feed-run increasing in size to the exit, and, further, of providing the grain-wheel with a hub attached to or forming part of same, the periphery of the hub following substantially the inner upper edge of the feed-run and the parts being constructed in detail as hereinafter more particularly explained.

Figure 1 is a perspective view of a cup and 25 double feed-run, showing the parts involved in my invention. Fig. 2 is a horizontal sectional plan through the feed-run and grain-wheel on a line with the center of the gate. Fig. 3 is an enlarged perspective view of the 30 cup and run with the grain-wheel and shaft removed.

In the drawings like letters of reference indicate corresponding parts in each figure.

Heretofore feed-runs in seeding-machines 35 have been a constant source of trouble on account of large grain, such as peas and the like, choking as they pass through the feed-run. It is with the object of providing a means to prevent the choking and allow the 40 grain to loosen and pass without crushing that my invention is particularly designed.

A is one-half of the casing or cup of a double feed-run, and B is the grain-wheel, which is suitably secured on an axle C, which extends through suitable bearings and holes c 45 in the casing. The grain-wheel B has provided, at one side thereof, the disk B', preferably tapered and secured to the grain-wheel.

A' is the feed-run, which is formed in the 50 usual manner at the top with a flaring mouth

a and a reduced portion a'. The lower portion a² of the feed-run is arc-shaped in form and has an outward flare or gradual increase in width and depth to a point in proximity to the perimeter of the wheel B. (See particularly Fig. 3.)

It will be noticed that the inner perimeter of the wheel B has a series of ribs b; but of course this is the usual construction in wheels of this class.

D is a gate which extends through a rectangular slot a³ midway of the length of the feed-run. The end of the gate is rounded off from top to bottom at d. The gate D is provided with a stem d', which extends through 65 a hollow boss A², attached to or forming part of the casing A of the feed-run. The outer end of the stem d' is threaded and extends through a nut D', which is provided with a series of diametrically-arranged notches d². 70 The cotter-pin or key d³ extends through the notches and the threaded end of the stem d'.

E is a spiral spring extending between the gate D and the outer end of the boss A².

By driving out the cotter-pin or key d³ and 75 turning the nut the tension of the spiral spring may be increased or diminished, so as to exert a greater or less force upon the gate D.

Although I describe the gate as held in position by the spring E, placed as described, 80 it will of course be understood that I might employ various other spring devices for holding the gate in position without departing from the spirit of my invention. The great point is to provide the gate at or near the 85 narrowest part of the feed-run in such a manner that when the grain is passing downwardly into the feed-run and binds at the smallest part the gate will yield on account of the spring and allow the grain to loosen 90 and pass through without crushing, when the gate will at once return to its normal position as soon as the jam is broken away.

I find in practice that the disk B', which is preferably attached to the side disk of the 95 center web of the grain-wheel, helps to a great extent to carry the grain through the wheel and run.

What I claim as my invention is—

1. In a seeding-machine, the combination 100

with the feed-run and grain-wheel, of a yieldingly-held gate located intermediately of the length of the feed-run adapted to have movement laterally of said wheel as and for the purpose specified.

5. In a seeding-machine, the combination with the feed-run and grain-wheel, of a gate extending through a slot in the narrowest part of the feed-run and projecting into the feed-run and a suitable spring for yieldingly holding the gate in position in the feed-run as and for the purpose specified.

6. In a seeding-machine, the combination with the feed-run and grain-wheel, of a gate 15 extending through a slot in the narrowest part of the feed-run and projecting into the feed-run and provided with a stem extending into a hollow boss in the casing of the feed-run, and a spring for normally pressing the gate into 20 the feed-run as and for the purpose specified.

7. In a seeding-machine, the combination with the feed-run and grain-wheel, of a gate extending through a slot in the narrowest part of the feed-run and projecting into the feed-run and provided with a stem extending into 25 a hollow boss in the casing of the feed-run, a spiral spring extending between the end of the boss and the gate and nut on the threaded end of the stem provided with end notches and 30 a cotter-pin extending through the threaded

end of the pin or stem and the notches of the nut as and for the purpose specified.

8. In a seeding-machine, the combination with the feed-run and grain-wheel, of a yieldingly-held gate located in the narrowest part 35 of the feed-run and means for adjusting the gate as and for the purpose specified.

9. In a seeding-machine, the combination with the feed-run and grain-wheel, of a yieldingly-held gate located in the narrowest part 40 of the feed-run and provided with a rounded upper end and a flat lower side meeting at an edge as and for the purpose specified.

10. A feed-run comprising a casing having a broad mouth at the upper end and a narrow 45 central portion and a flaring arc-shaped discharge end for the run and a gate adapted to yield laterally situated in the narrowest part of the run as and for the purpose specified.

11. The combination with the feed-run, of 50 the grain-wheel and axle, and the disk located adjacent to the wheel adapted to rotate therewith and substantially on the same arc as the arc of the feed-run as and for the purpose specified.

CHARLES MCLEOD.
